(57) **CLAIM**

The ornamental design for a watch dial, substantially as shown and described.

DESCRIPTION

FIG. 1 is a perspective view of the watch dial of the present invention;

FIG. 2 is a front view of the watch dial shown in of FIG. 1; FIG. 3 is a rear view of the watch dial shown in of FIG. 1; FIG. 4 is a left side elevational view of the watch dial shown in of FIG. 1;

FIG. 5 is a right side elevational view of the watch dial shown in of FIG. 1;

FIG. 6 is a top view of the watch dial shown in of FIG. 1; and,

FIG. 7 is a bottom view of the watch dial shown in of FIG. 1.

The terms "RESERVE DE MARCHE" and "REPETITION MINUTES" shown in broken lines in FIGS. 1 and 2 are for purposes of illustration only and form no part of the claimed design.
